HOUSING FOR BREATHING APPARATUS

Manfred K. Hegemann, Nyack, N.Y., assignor to The Firewel Company, Inc., Buffalo, N.Y.

Filed Apr. 4, 1966, Ser. No. 1,781

Term of patent 14 years

(Cl. D83—1)

FIG. 1 is rear elevation of a housing for breathing apparatus embodying my new design.

FIG. 2 is a top plan view thereof.

FIG. 3 is a bottom plan view thereof.

FIG. 4 is a front elevational view thereof.

FIG. 5 is a side elevational view thereof, the opposite side view being substantially the same.

FIG. 6 is a sectional view taken of line 6—6, FIG. 1.

I claim:

The ornamental design for a housing for breathing apparatus, substantially as shown and described.
